(57) CLAIM

The ornamental design for a luggage scale.

DESCRIPTION

FIG. 1 is an isometric view of the luggage scale;

FIG. 2 is a front plan view of the luggage scale of FIG. 1;

FIG. 3 is a top plan view of the luggage scale of FIG. 1;

FIG. 4 is a right side elevation of the luggage scale of FIG. 2;

FIG. 5 is a back plan view of the luggage scale of FIG. 2;

FIG. 6 is a left side elevation of the luggage scale of FIG. 2; and,

FIG. 7 is a bottom plan view of the luggage scale of FIG. 2.

The broken line showing of structural features is included for the purpose of illustrating non-claimed subject matter and forms no part of the claimed design.

1 Claim, 3 Drawing Sheets
